UNITED STATES PATENT OFFICE

WILLIAM HEWIG, OF BATTLE CREEK, MICHIGAN, ASSIGNOR TO H. B. SHERMAN MANUFACTURING COMPANY, OF BATTLE CREEK, MICHIGAN, A CORPORATION OF MICHIGAN

REVERSIBLE SOAP DISH FOR DOUBLE MIXING FAUCETS

Application filed May 17, 1930, Serial No. 453,278. Renewed November 9, 1931.

This invention relates to so-called double or mixing faucets in which two faucets are twinned together so that they have separate supply connections and a common discharge outlet, such for instance as are used for shower bath faucets, laundry or sink faucets, and so that hot and cold water may be supplied to the respective faucets and discharged separately or together through a common outlet.

The invention is particularly adapted for use in connection with a faucet such as shown in my companion application filed February 24, 1930, Serial No. 431,024.

The object of the present invention is to provide a detachable member such as a soap dish which can be readily attached to or detached from the supporting body or faucet body, whether the latter is positioned with the discharge uppermost or lowermost, or whether the faucet be arranged with one side or the other against the wall or outermost; such soap dish being detachably attachable to the double faucet body without screws or other fastenings to be manipulated; and will be securely and properly retained in position while so attached, but can be readily detached if it is desired to cleanse same.

A further object of the invention is to enable the soap dish to be attached to either side of the double faucet body, whether it be attached to the pipes with the discharge uppermost or lowermost.

The invention provides a soap dish and novel means for securely detachably attaching the soap dish to the supporting body in any position desired without the use of bolts or rivets or other fastenings which have to be manipulated and whereby drilling or machining of the body or the soap dish will be unnecessary.

I will describe the invention with reference to the accompanying drawings which illustrate the same, and summarize in the claims the novel features of construction and novel combinations of parts for which protection is desired.

In the drawings:

Fig. 1 illustrates a soap dish attached to a double mixing faucet adapted for use as a shower bath fixture.

Fig. 2 is a view showing the same soap dish attached to the same faucet the latter being inverted for use as a laundry faucet.

Fig. 3 is an enlarged transverse sectional view of the soap dish and part of a faucet or supporting body, showing the manner of attaching the dish thereto.

Fig. 4 is a detail view looking down upon the dish supporting devices.

Fig. 5 is a bottom view of the parts shown in Fig. 4.

Fig. 6 is a detail view showing the connection between a bracket and a body lug; and

Fig. 7 is a transverse section on the line 7—7, Fig. 6.

The laundry faucet or body may be of any suitable construction. In the construction shown it has a U-shaped body having at one end a hot water inlet H, and at the other a cold water inlet C, and an intermediate common outlet connected to a spout S; and suitable valves V are interposed, in the bifurcations or parts 3, 3, of the body, respectively between the hot water inlet and the outlet, and between the cold water inlet and the outlet.

The body is preferably provided at opposite sides of the outlet with lugs 1, each of which is preferably triangular in transverse cross section (see Figs. 6 and 7), the apex of the triangular being innermost and point toward the outlet and the base of the triangle being outermost. The outer edges of the lug at the base of the triangle are notched, as at 1a, for engagement of retaining flanges 2a on the supporting brackets B.

Each bracket B is provided with a recess 2, preferably angular in transverse cross section, and complementary to the angular end of the lug 1 which it is adapted to receive; and also with malleable flanges 2a at opposite sides of the recess which, after the lug 1 is entered in the recess, are turned down over the outer face of the lug 1 and into engagement with the notches 1a, as indicated in Figs. 6 and 7. When thus engaged it is impossible for the brackets to become detached from the body unless the parts should break. The body and brackets can be made separately and rigidly connected together expeditiously

and securely. This means for attaching the bracket to the body is more fully described and claimed in my aforesaid application Serial No. 431,024.

5 In the present invention the members or parts 3 of the faucet or supporting body are provided on their opposite faces with pairs of projecting lugs 3a, 3b (see Figs. 3-5) which are slightly spaced apart and preferably 10 cylindric.

The soap dish 4, may be made of any desired form, a conventional form being illustrated in the drawings, and is provided at its rear side with a rearwardly extending flange 15 4a which is about as wide as the space between the adjacent members 3 of the body. The inner end of the flange 4a is upturned, as at 4b, and is adapted to hook under and in rear of the upper lugs 3a, as shown in Figs. 3 and 4. 20 At the sides of the flange 4a and underneath the same are stiffening ribs 4c, which extend from the rear side of the soap dish body toward the curved end of the flange 4a, and have their rear ends cut away as at 4d to form 25 shoulders which engage the lugs 3b, the reduced portion of the ribs 4c projecting over the lugs 3b as shown at 4e, Fig. 3.

To place the soap dish in place it is tilted and the curved end 4b of flange 4a entered 30 between the pairs of lugs 3a, 3b until the shoulders 4d engage the lugs 3b; then the soap dish is turned to horizontal position causing end 4b of the flange to engage the lower and rear sides of lugs 3a and the shoulders 4d to engage the upper and front sides 35 of the lugs 3b. The dish will then be securely held in position by its own weight; and is prevented from any lateral play by the fit of the flange between the parts 3 of the faucet 40 body, and is prevented from vertical play by its own weight and the close fit of the shoulder portions 4b and flange 4a between the lugs 3a, 3b. When the dish is in proper position there will be no chatter or vertical play 45 of the ribs or flanges between the lugs 3a, 3b. The dotted lines, Fig. 3, show how the soap dish could be inserted from the other side of the body. Figs. 1 and 2 show how the soap dish can be engaged with the double 50 faucet whether its discharge is uppermost or lowermost.

I claim:

1. Means for detachably attaching a soap dish to a faucet; consisting in providing adjacent opposed portions of the faucet body with pairs of inwardly extending lugs; and providing the soap dish with a rearwardly extending flange adapted to be entered between the said portions and pairs of lugs, the 55 inner end of said flange being upturned to engage the under and rear sides of the uppermost lug in each pair and having shoulders adapted to engage the upper and front sides of the lowermost lug in each pair, 60 whereby the soap dish is supported and con-

fined in position on the body by engagement with the lugs.

2. Means for detachably attaching a soap dish to a double faucet and the like; comprising pairs of lugs on the opposed faces of opposite members of the faucet body; and a rearwardly extending flange on the soap dish adapted to be entered between the said members and between the lugs, the inner end of said flange being upturned to engage the under and rear sides of the uppermost lug in each pair, and ribs on said flange adjacent opposite ends thereof having shoulders adapted to engage the front and top sides of the lowermost lug in each pair; the soap dish being supported and confined in position by the engagement of the upturned end of the flange with the upper lugs, and the engagement of the shoulders with the lower lugs.

WILLIAM HEWIG.
